UNITED STATES PATENT OFFICE.

ELMOR RANDOLPH CARRINGTON, OF MONTREAL, QUEBEC, CANADA.

RAILWAY-PASSENGER-CAR CONSTRUCTION.

No. 902,855.

Specification of Letters Patent.

Patented Nov. 3, 1908.

Application filed March 30, 1908. Serial No. 424,206.

To all whom it may concern:

Be it known that I, ELMOR RANDOLPH CARRINGTON, a citizen of the United States of America, residing at 112 St. James street, 6 in the city and district of Montreal, in the Province of Quebec, in the Dominion of Canada, have invented certain new and useful Improvements in Railway-Passenger-Car Construction, of which the following is a 10 specification.

The invention relates to a railway passenger car construction, as described in the present specification and illustrated in the accompanying drawings that form part of 15 the same.

The invention consists essentially in the novel arrangement and construction of parts whereby a front wall forms a support for a speaking trumpet the latter extending into 20 the vestibule in proximity to the position occupied by the vehicle attendant.

The objects of the invention are to devise a simple and efficient means of conveying 25 announcements made by the motor man in a street car to the passengers inside of the body of the car, particularly such as the name of each cross street as the car approaches it, to provide a construction in such means that will be convenient to the 30 motor man and whereby the conveyance of the sound of his voice will be much facilitated, and generally to substitute by the use of mechanical contrivances a new method of furnishing from the outside to the 35 passengers of any vehicle information in distinct sounds that the car is nearing a stop or place of interest.

In the drawings, Figure 1 is an interior view of street car of modern design, in perspective, showing the sound conveyer projecting through a transom wall. Fig. 2 is a perspective view of the front end of a car showing the side of the vestibule partially broken away to disclose the arrangement of 45 the sound conveyer. Fig. 3 is a longitudinal sectional view of the sound conveyer apart from the car. Fig. 4 is a sectional view of the vertical portion of the sound conveyer.

50 Like numerals of reference indicate corresponding parts in each figure.

Referring to the drawings, 1 is the car body, 2 the front vestibule and 3 the partition or front side of the body dividing said vestibule from the interior of said body. 55

4 is a transom partition surmounting the partition 3 and having a hole 5 therethrough, here shown as in the center, though the said hole may be in any suitable place in said transom partition or through the partition 3, 60 in fact as long as the hole furnishes communication between the front vestibule and the interior of the body of the car, it may be arranged in any likely place that will not interfere materially with the car structure. 65

6 is a hood forming a continuation of the upper portion of the main roof of the car extending forwardly on to and joining the vestibule roof 7. 70

8 is a horn here shown as a well known type of speaking trumpet, though it may be made in any shape offering special facilities for the conveyance of sound, the horn 8 projects through the hole 5, at its large and flaring end, and extends forwardly converging to 75 the narrow neck 9 leading through the hole 10 in the ceiling 11 of the vestibule, so that the said horn is contained within the hooded portion of said vestibule.

12 is a tube vertically and telescopically 80 arranged at 13 on the downwardly projecting end of the neck 9. The said telescopic arrangement may be entirely in the tube 12 or in any other manner.

14 is a sound box joined to the lower end 85 of the tube 12 and communicating therewith having the aperture 15, into which the car attendant speaks, so that the voice resonates in said box and is carried through the tube 12, the narrow neck 9 and the main horn 8, 90 sounding forth from the flaring end of said horn into the interior of the car.

What I claim as my invention is:

In railway passenger car construction, a body portion, a front vestibule rigidly secured to said body, a wall separating the interior of said body portion from said front vestibule, said wall having an opening therethrough adjacent to the top thereof, a ceiling in said vestibule having a hole therethrough, 95 a funnel-shaped speaking trumpet having its flaring bell adjacent to the extremity abut- 100

ting said wall at said opening and its narrow neck end extending through said ceiling hole, and a vertically adjustable resonating box depending from said ceiling and communicating with said narrow neck and having a mouth piece facing in the same direction as said flaring bell.

Signed at the city and district of Montreal, in the Province of Quebec, in the Dominion of Canada, this 11th day of March, 1908.

ELMOR RANDOLPH CARRINGTON.

Witnesses:

HARRY DAVIS,
G. H. TRESIDDER.
